HAIR WAVING MACHINE

Frank Laver, Chicago, Ill., assignor to A. B. C.
Oil Burner Sales & Service Corporation, a cor-
poration of Illinois

Application October 14, 1935, Serial No. 44,963

9 Claims. (Cl. 132—36)

My invention relates to electrical hair waving machines for use in the heating of the hair to be curled or waved and wound upon curling rods in accordance with common practice.

5 Machines of this kind are commonly provided with a relatively large number of curling heater devices flexibly suspended through the medium of their current conducting leads, over the head of the person whose hair is to be curled or waved, 10 the heater devices being adapted for selective clamping to the different portions of the person's hair to be operated on and the leads to the heaters being associated with devices whereby the leads will extend from the heaters to the supporting structure above, in a substantially straight line.

My invention as to one of its features relates to the manner of supporting the current leads whereby the leads from their points of connection with the heater devices to the support from which 20 they depend may be caused to extend in the desired substantially taut, or straight line, condition, and be readily separately adjustable to cause the heater devices to extend at the heights desired, without undue wear of the parts, and entanglement of one lead with another.

Another object is to provide a machine which will be free of exposed wire loops and such other parts commonly used as add objectionable weight 30 to the head of the person whose hair is operated on.

Another object is to provide a machine whereby the possibility of objectionable electric contacts producing uneven heating of the heater devices will be avoided.

35 Another object is to provide for the accurate adjustment, with ease, of the height to which the several heater devices extend with resultant closer and better waving than possible with machines 40 as hitherto provided.

Another object is to provide a machine presenting the adaptability for adjustment of the leads as above stated which will be of simple construction, and whereby danger of impairment of 45 its parts resulting in the burning of the person whose hair is being operated on, will be reduced to the minimum; and other objects as will be manifest from the following description.

50 Referring to the accompanying drawings: Figure 1 is a broken view in side elevation, of a machine embodying my invention.

Figure 2 is a plan sectional view taken at the line 2 on Fig. 1 and viewed in the direction of the arrow.

Figure 3 is a diagrammatic view showing the electrical circuit connections of the machine.

Figure 4 is a broken view in vertical sectional elevation of the construction shown in Figs. 1 and 2, the section being taken at the line 4 on Fig. 2 and viewed in the direction of the arrow.

Figure 5 is a broken plan sectional view through one of the similar lead-supporting and adjusting devices and the support therefor, the section being taken at the line 5 on Fig. 4 and viewed in 10 the direction of the arrow.

Figure 6 is a similar view taken at the line 6 on Fig. 4 and viewed in the direction of the arrow.

Figure 7 is a view in the nature of a diagram 15 of one of the similar contact plugs and its circuit connections with the coils of two electric heater devices of the spiral type; and

Figure 8, a similar view of one of the similar contact plugs and its circuit connections with the coils of two sectional clamp Croquignole electric heater devices.

Figure 9 is a view in the nature of a diagram 20 of one of the similar contact plugs and its circuit connections with the coils of two electric heater devices of the spiral type; and

Figure 10 is a view in the nature of a diagram 25 of one of the similar contact plugs and its circuit connections with the coils of two sectional clamp Croquignole electric heater devices.

The particular illustrated embodiment of my invention comprises a supporting member shown as in the form of a hollow vertically disposed shell 9 which may be supported in any desirable way, as for example on a post 10 vertically adjustable in a hollow standard 11 which in practice would rest at a base portion thereon on the floor. The machine also comprises electrical heating devices, current-conducting leads extending from the heating devices into the shell and supporting the heating devices to extend below the shell, wherein they are connected with outlet sockets carried by the shell, and elevation-controlling devices connected with the current conducting leads between their ends and supported on the shell for vertical adjustment thereon. In the construction shown two well known types of electric heaters are illustrated by way of example, one, the Croquignole type, exemplified at 12, and the other the spiral socket type exemplified at 13. Two only of each of these two types of heater devices are shown, there being provided as many of each type as desired. The machine shown is adapted for energizing twenty heaters of each of the two types referred to.

As usual, the Croquignole type 12 is a split clamp form comprising the two clamp portions 14 each of which contains a section of an electric heating element, two sections of heating elements for the two clamp portions 14, being shown at 15. The spiral type 13 of heater device, which contains a socket in its outer end to receive the 55

hair would on curling rods, comprises a single heating element as represented at 16.

Each pair of heating element sections 15 is connected together in series and with current conducting leads represented at 17, the leads 17 for each pair of adjacent heaters 12 being connected in parallel with an electric push-plug 18 as shown particularly in Fig. 8.

The heater element 16 of each spiral heater 10 13 is connected with current conducting leads 19, the leads for each pair of adjacent heaters 13 being connected in parallel with an electric push-plug 20 as shown more particularly in Fig. 7.

15 The shell 9 comprises a hollow cylindrical member 21 secured to the post 10 through the medium of the housing 22 of current-controlling mechanism hereinafter referred to, the member 21 having a series of vertical slots 23, shown as forty 20 in number, disposed about its circumference. The member 21 is connected at its lower end with a circular plate 24 containing apertures 25 disposed in circular series around the margin thereof, there being twenty of these apertures each to 25 receive the leads of a pair of electrically connected heater devices. The member 21 and plate 24 are connected together by means of a ring 26 at the outer edge of the plate 24 and angles 27 secured to the plate 24 by bolts 28, the lower 30 edge of the member 21 extending into the annular space 29 between the rings 26 and angles 27 and secured thereto by bolts 30.

The upper end of the member 21 carries a removable cover plate 31 shown as of dome shape 35 and extending at its annular lower rim portion 32 into the upper end of the member 21 and resting on angle lugs 33 secured to the member 21 as by bolts 34 which also secure to the member 21 a finishing band 35 applied to the outer side 40 of the member 21.

45 The current conducting leads from each heater device are independently connected between their ends with a series of elevation-controlling devices 36 carried by, and arranged around the circumference of, the member 21, whereby the elevation at which each heater device extends may be easily controlled as desired, forty of these controlling devices being provided in the particular construction shown for cooperation with 50 the forty heater devices.

55 Each controlling device 36 comprises a bar portion 37 which extends through one of the vertical slots 23 in the member 21; and a head, or knob, 38 of current insulating material secured to the outer end of the bar 37 as for example by molding it in anchored position on the head, the bar 37 containing an opening, or openings, 39 to receive a portion of the molded head-forming material. The head thus exposed at the outer 60 side of the member 21 serves as a means by which the operator may vertically adjust the device 36. The device 36 also comprises a cross pin 40 in the inner end of the bar portion 37 between which and a washer 41 on the bar 37, a loop portion 42 of the twisted leads is confined; and a coiled spring 43 surrounding the bar portion 37 and interposed between the washer 41 and the member 21 and frictionally holding the device 65 36 to the member 21 in all of its positions of vertical adjustment thereon.

70 Preferably the portions forming the loop 42 are sheathed in split rubber protectors 44 and the leads above and below, and closely adjacent to, the bar are secured together by metal clips 42a which as shown, may be of strip form each hav-

ing a tongue at one end for insertion through a slot in the other end of the clip, the tongue being drawable through the slot to produce the desired clamping effect and bent back to hold the clip in clamping position.

5 The machine also comprises electric sockets mounted on the plate 24 for receiving the plugs 18 and 20.

Ten sockets 45 for receiving the plugs 18, 10 respectively, of the Croquignole heater devices 12, and ten sockets 46 for receiving the plugs 20, respectively, of the spiral heater devices 13 are provided, the sockets 45 being arranged in one circuit and the sockets 46 in another with controlling means for directing current to either 15 group of sockets as desired.

Six of each of both groups of sockets are shown 20 secured to the plate 24 by yoke-shaped members 47 and 48, respectively, fastened to the plate 24 by screws 49 and the remaining four of each 25 of both groups of sockets are shown secured to the plate 24 by Z-shaped members 50 and 51, respectively, fastened to the plate 24 by screws 52.

The plate 24 also carries sockets 53 and 54 25 for two electric signal lamps 55 and 56, respectively, of different colors as for example green and red, respectively, secured to the plate 24 by screws 57, the sockets 53 and 54 being connected in series with the groups of sockets 45 and 46, respectively, to indicate to the operator which 30 group of heater devices are being energized.

As customary in machines of this general character switch means hereinbefore referred to and 35 represented at 58 and 59 and located in the housing 22 and having turn buttons 60 and 61, respectively, are provided for selectively directing current through the different kinds of heater devices 12 and 13, with time control mechanism incorporated therewith, whereby the current may be caused to flow to the energized heater devices 40 for any one of a number of selected periods of time.

45 Referring now to the electrical circuit diagram shown in Fig. 3, the main line wires are represented at 62 and 63 and connect with the terminals 64 and 65 of a volt meter 66 also mounted in the housing 22.

The sockets 45 are connected in parallel by 50 means of wires 67—83, inclusive, the wires 67—74 constituting one side of the circuit and the wires 75—83 constituting the other side of the circuit, one side of the parallel circuit being connected with the lead 62 at the wire 67 and the other side of this circuit connected with one terminal 84 of the switch 58 by a wire 85 connected with the 55 wire 75.

The sockets 46 are connected in parallel by 60 means of wires 86—102, inclusive, the wires 86—94 constituting one side of the circuit and the wires 95—102 constituting the other side of this circuit, one side of this circuit being connected with the lead 62 by a wire 103 connected with the wire 101 and the other side of this circuit being connected with the terminal 104 of the switch device 59 by a wire 105 connected with the wire 87.

65 The other terminals 106 and 107 of the switch devices 58 and 59, respectively, are connected together by a wire 108 which connects with the lead 63.

70 From the foregoing it will be understood that the closing of the switch 58 will cause current to be supplied to all of the sockets 45 for the Croquignole heater devices; and that when the switch 75

59 is closed it will supply current to all of the sockets 46 for the spiral heater devices.

The sockets 53 and 54 are interposed in series in a wire 109 which connects with the wire 75, 5 and with the wire 94, a shunt circuit around the socket 54 being provided by a wire 110 which connects with the wire 95 and with the wire 109 between the sockets 53 and 54. As will be understood, when current is being supplied to the 10 sockets 45 (the switch 58 being closed and the switch 59 open) current will also pass through the socket 53, the current passing over the wires 85, 75, and 109 (through the socket 53 and to the wire 110), and thence through wires 95—101, 15 inclusive, to wire 105. When the switch 58 is open and the switch 59 closed, current will pass through the socket 54 which, by reason of the provision of the wire 110, is in effect in parallel with the sockets 46.

20 In the use of the machine the several elevation-controlling devices would be adjusted vertically on the member 21, independently of each other, to cause the heater devices to extend at the exact elevations desired, depending on the particular condition presented by the person whose hair is to be waved, it being understood that it is desirable that the heater devices be adjusted to such an elevation as to preclude objectionable slack and still avoid any undue pulling stresses 25 on the hair; the waving of the hair by the machine being effected by the heater devices in accordance with common practice.

The construction shown not only greatly minimizes wear on the leads and resistance to adjustment of the heater devices in a vertical direction and minimizes danger of interference between looped leads within the shell, but affords means whereby the most delicate and accurate adjustments of the heater devices may be effected 40 to the end not only of adapting the machine for the performance of its work in a highly satisfactory manner, but minimizes inconvenience and danger to the person whose hair is being operated on.

45 Furthermore, the machine by reason of the provision of the shell as shown and described provides means for the ready upward escape of the heat from the heater devices, thus minimizing discomfort to the person whose hair is being 50 operated on, the shell, in effect, forming a flue which tends to draw the heat upwardly therethrough.

The signal lamps referred to not only serve to indicate to the operator which set of heater devices are being energized, but also serve in their use in connection with an open-work shell to afford an attractive mode of illumination of the interior of the shell.

60 While I have illustrated and described a particular construction constituting my invention, I do not wish to be understood as intending to limit it thereto as the same may be variously modified and altered without departing from the spirit of 65 my invention, it being my intention to claim my invention as fully and completely as the prior state of the art will permit.

What I claim as new, and desire to secure by letters patent, is:

70 1. A hair waving machine comprising a supporting structure, electric heater devices, and means for supporting and energizing said heater devices comprising flexible conductors and means 75 engaging said conductors and said supporting structure and slidably adjustable up and down on

the latter into selected set positions to vary the height at which said heater devices extend.

2. A hair waving machine comprising a supporting structure, electric heater devices, and means for supporting and energizing said heater devices comprising flexible conductors and means engaging said conductors and slidably adjustable up and down on the latter to vary the height at which said heater devices extend and held in adjusted position by frictional engagement with 10 said supporting structure.

3. A hair waving machine comprising a supporting structure, electric heater devices, and means for supporting and energizing said heater devices comprising flexible conductors and means 15 engaging said conductors and said supporting structure and slidably adjustable up and down on the latter into selected set positions to vary the height at which said heater devices extend and having portions exterior of said supporting structure by which to separately adjust said second-named means on said supporting structure.

4. A hair waving machine comprising a supporting structure, electric heater devices, and means for supporting and energizing said heater devices comprising flexible conductors and means 20 engaging said supporting structure and said conductors at portions thereof above the lower portion of said supporting structure and slidably adjustable up and down on the latter to vary the 25 height at which said heater devices extend.

5. A hair waving machine comprising a supporting structure, electric heater devices, and means for supporting and energizing said heater devices comprising flexible conductors and means 30 engaging said conductors and said supporting structure and slidably adjustable up and down on the latter to vary the height at which said heater devices extend and having portions extending laterally through said supporting structure to 35 the exterior thereof by which to separately adjust said second-named means up and down on said supporting structure.

6. A hair waving machine comprising a shell 40 having upwardly extending slots in its side wall, electric heater devices, and means for supporting and energizing said heater devices comprising flexible conductors and means extending in said 45 slots and engaging said conductors and said supporting structure and slidably adjustable up and down in said slots to vary the height at which said heater devices extend.

7. A hair waving machine comprising a shell 50 having upwardly extending slots in its side wall, electric heater devices, and means for supporting and energizing said heater devices comprising flexible conductors and means extending in said 55 slots and engaging said conductors and frictionally engaging said supporting structure and slidably adjustable up and down in said slots to vary the height at which said heater devices extend.

8. A hair waving machine comprising a shell 60 having upwardly extending slots in its side wall, electric heater devices, and means for supporting and energizing said heater devices comprising flexible conductors and elevation-controlling devices on said shell comprising bars slidable up and down in said slots and engaged by said conductors to move therewith, heads on the outer ends of said 65 bars and springs engaging said bars and shell and frictionally holding said devices in adjusted position along said slots.

9. A hair waving machine comprising a shell 70 having upwardly extending slots in its side wall, 75

electric heater devices, and means for supporting and energizing said heater devices comprising flexible conductors and elevation-controlling devices on said shell comprising bars slideable up and down in said slots and engaged by said conductors to move therewith, heads on the outer ends of said

bars, projections and washers on the inner ends of said bars, the leads being confined between said projections and washers, and springs engaging said washers and shell and frictionally holding said devices in adjusted position along said slots. 5

FRANK LAVER.
